CHENEY KILBURN, OF PHILADELPHIA, PENNSYLVANIA, ASSIGNOR TO
KILBURN & GATES, OF SAME PLACE.

Design No. 4,460, dated November 8, 1870.

DESIGN FOR BOXES FOR THE TOPS OF BUREAUS.

The Schedule referred to in these Letters Patent and making part of the same.

I, CHENEY KILBURN, of Philadelphia, county of Philadelphia, State of Pennsylvania, have invented or produced a Design for Boxes for the Tops of Bureaus, of which the following is a specification.

On reference to the accompanying drawing—

Figure 1 is a perspective view of a box, made in accordance with my design;

Figure 2, a plan view of the same; and

Figure 3, an enlarged sectional view, illustrating the design of the molding or finish for the edge of the box.

The front and sides of the box are formed upon a continuous curve of such a character that the box shall be somewhat narrower at the back than at a point between the latter and the front of the box.

The outline of the box represented in the drawing consists, for instance, of a part of a circle described from the point *a*, on a line, *z z*, parallel with the back of the box, and it will be observed, on reference to fig. 2, that the distance between the opposite sides of the box on this center line is greater than upon the line *y y*, which represents the back of the box.

The same effect may be produced, without depart-

ing from my design, in a box formed on an oval or elliptical curve, providing that the box be narrower at the back than at a point in advance of the latter.

The molding or finish for the edge of the box is of the peculiar design plainly illustrated in fig. 3.

I claim—

1. A box for the tops of bureaus, having its front and sides (or ends) formed upon a continuous curve of such a character that the box shall be narrower at the back than at a point between the latter and the front of the box, all substantially as described and illustrated.

2. The design of the molding or finish for the edge of the box, substantially as described, and as represented in and by the accompanying drawing.

In testimony whereof, I have signed my name to this specification in the presence of two subscribing witnesses.

CHENEY KILBURN.
